FINGER RING

Howard S. Canfield, Atlanta, Ga.

Application March 28, 1956, Serial No. 40,816

Term of patent 7 years

(Cl. D45—10)

FIG.-1

FIG.-2

FIG.-3

Fig. 1 is a front view of a finger ring, showing my new design.

Fig. 2 is an elevational view of one side of the ring.

Fig. 3 is an elevational view of the opposite side of the ring.

I claim:

The ornamental design for a finger ring, as shown.
